UNITED STATES PATENT OFFICE.

WILLEVE T. MERRIMAN, OF MINNEAPOLIS, MINNESOTA.

AUTOMATIC STREET-RAILWAY SWITCH.

SPECIFICATION forming part of Letters Patent No. 460,146, dated September 29, 1891.

Application filed March 28, 1891. Serial No. 386,836. (No model.)

To all whom it may concern:

Be it known that I, WILLEVE T. MERRIMAN, a citizen of the United States, residing at Minneapolis, in the county of Hennepin and State of Minnesota, have invented certain new and useful Improvements in Automatic Street-Railway Switches; and I do hereby declare the following to be a full, clear, and exact description of the invention, such as will enable others skilled in the art to which it appertains to make and use the same.

My invention relates to street-railway switches, and has for its object to provide a simple and efficient construction for operating the same automatically from the car. To this end, in addition to the switch-lever for swinging the pivoted rail I provide inclined guideways fixed in the path of the car, and in the guideways I place slides having connections with the switch-lever; and for co-operation therewith I place strikers on the car, adapted to be set in a position to strike the slides and operate the switch. The inclination of the guides is such that the slide will clear the striker on reaching the foot of the guide. Each car carries a pair of strikers—one on each side—in position to strike the corresponding member of the pair of slides. The slides and their connections to the switch-lever are so arranged that one will open and the other close the switch. The strikers carried by the car can only strike the slides when at the head of their guides. Hence if the switch-rail is in its proper position the switch will not be touched by the striker. It is only necessary for the car-driver to set his striker for either the main line or the branch and the car will take care of itself. If set for the main line and the switch be closed, the striker will strike the slide and open the switch. If set for the branch line and the switch be opened, the striker will strike the other slide and close the switch. The inclined guides are conveniently formed of plates having inclined slots, the plates being adapted to be secured to the fixed rails between the upper and lower flanges of the same.

The construction is illustrated in the accompanying drawings, therein like letters referring to like parts throughout. Figure 1 is a plan view of a part of the main and branch

tracks of a street-railway, and the switch in working position. Fig. 2 is a side elevation of the car and a part of the track, some portions being broken away; and Figs. 3 and 4 are details in side elevation and cross-section, respectively, of the inclined guides and the slides in position on one of the fixed rails.

A A are the fixed rails of the main line, 60 and B B are the rails of the branch line.

C is the pivoted or switch rail.

D is a three-arm switch-lever pivoted, as shown at d, to some suitable support between the rails.

D' is the connecting-rod uniting the same with the free end of the switch-rail.

E are the plates, with inclined slots, as shown at e, constituting the inclined guides, securable to the inner faces of the fixed rails 70 A A by bolts and nuts F G between the upper and lower flanges of the rail, as shown in Figs. 3 and 4.

H are the slides mounted in said guides, and K are the connecting-rods uniting the slides 75 with the extremities of the switch-lever D. The slides H are formed with T-shaped heads, and are placed in position in their guides from the back of the plate before the plate is secured into position. They will then 80 be held so they cannot be displaced without removing the plate. The heads project beyond the inner face of the plates, so that, taken together with the raised end of their connecting-rods K, their projecting parts constitute a suitable striking-surface for the 85 striker carried by the car.

L represents an ordinary street-car in position on the main line approaching the switch. The front end of the car at the 90 right-hand corner and the right-hand rail are broken away to expose the left-hand striker and the left-hand slide.

M is the guard-board or other part of the car-truck, which is supported directly on the 95 axle of the car-truck independent of the car-body, so as to preserve a constant position with reference to the rails.

N is the striker, represented as mounted in a socket M', fixed to the guard-board and 100 vertically movable therein.

P is a cord attached to the head of the striker and passing through a perforation in the front platform and up over a sheave p,

secured to the roof and provided on its free end with a hand-pull P', within reach of the driver. A projecting stud or holder Q may be provided, with which the hand-pull may be made to engage to hold the striker in its uppermost position. The striker may be of such weight that when released it will fall to its lowermost or striking position by gravity. The striker on the other side of the car is 10 exactly similar.

The operation has already been described. The advantage of a device of this kind is apparent. It is especially serviceable on electric systems now going into extensive use. 15 Without some such device the car must be stopped to set the switch, and the practice is to carry a hand-lever on the car, with which the driver reaches over the front platform, after stopping the car, to set the switch. 20 This takes considerable time. With my device the car would not need to be stopped, but would of itself take care of the switch. The construction is so simple that it is reliable and durable.

25 It will of course be understood that the

switch-lever D and its connections D' K K would in practice be protected from the street traffic by a suitable shield or cover.

What I claim, and desire to secure by Letters Patent of the United States, is as follows: 30

1. The combination, with the switch-lever, of inclined guides securable to the fixed rails of the main track between the upper and lower flanges of the same slides mounted in said guides, connections from the same to 35 said switch-lever, and strikers carried by the car for co-operation with the slides to control the switch, substantially as described.

2. The combination, with the switch-lever, of the plates having inclined slots securable 40 to the fixed rails, the T-shaped slides mounted in the said slots, the connections from the same to the switch-lever, and the strikers on the car, substantially as described.

In testimony whereof I affix my signature in 45 presence of two witnesses.

WILLEVE T. MERRIMAN.
